UNITED STATES PATENT OFFICE.

GIUSEPPE DE MERCURIO, OF HAMMONTON, NEW JERSEY.

ROLLING WINDOW SCREEN.

Application filed February 10, 1927. Serial No. 167,230.

This invention relates to certain new and useful improvements in rolling window screens of that type wherein the flexible screen element is normally wound upon a 5 spring operated roller journaled in a horizontal position at the top of the window at the outside of the latter, and adapted to be manually pulled downwardly and releasably held in unrolled operative position against 10 the action of the roller operating spring.

The primary object of the present invention is to provide a rolling window screen equipment for windows, of the above kind, which is extremely simple and durable in 15 construction as well as efficient in use.

A more specific object of the invention is to provide simple and effective improved guiding means for the longitudinal edges of the flexible screen element, by means of 20 which entrance of insects and the like into the building between the longitudinal edges of the screen element and the sides of the window frame is effectively prevented, while maintainance of the screen element in taut 25 condition is insured when said screen element is unrolled.

Other objects will become apparent as the nature of the invention is better understood, and the same consists in the novel form, 30 combination and arrangement of parts hereinafter more fully described, shown in the accompanying drawing and claimed.

In the drawings wherein like reference characters indicate corresponding parts 35 throughout the several views,

Figure 1 is a fragmentary exterior elevational view showing a window equipped with a rolling window screen constructed in accordance with the present invention, and 40 with the screen roller housing removed;

Figure 2 is a fragmentary vertical section with the roller housing in place and taken substantially upon the line 2—2 of Figure 1; and

Figure 3 is an enlarged fragmentary horizontal section taken upon line 3—3 of Figure 1 to reveal details of the guiding means for the flexible screen element.

Referring more in detail to the drawing, 50 5 indicates a hollow sheet metal roller having one end of a flexible screen element or reticulated wire fabric 6 suitably fastened thereto, and suitably actuated or rotated by means of a spring 7 for normally winding 55 the screen element 6 thereon. The ends of the roller 5 are suitably journaled in bear-

ing brackets 8 secured in horizontally aligned relation on the outside of and to the ends of the top member 9 of the window frame. A suitably shaped sheet metal housing 10 is provided to encase the roller 5 and bearings 8, the same being open at its rear side and having flanges or ears at this side for facilitating its attachment to the frame member 9 as at 11. The housing 10 is preferably shaped to readily shed rain and the like and to have the free edges of its end and top walls to abut the face of the window frame member 9 throughout so that the rain and the like will be excluded, while the bottom wall of the housing terminates in slightly spaced relation to the window frame member 9 as shown in Figure 2 so that the screen element may extend out of the housing for being pulled downwardly and unrolled to 75 a position between the sides of the window frame as illustrated in Figure 3.

The free end of the screen element 6 is bound by means of a folded sheet metal strip held to the end of the screen element 80 by being clinched thereon through pressure of the folded portions of the sheet metal strip 12 into firm engagement with opposite sides of the screen element, as will be readily understood. This strip 12 is shaped of angular form as shown clearly in Figure 2 so as to define a vertical portion gripping the end of the screen element and a lower horizontal portion adapted to seat flatly upon the upper surface of the bottom member of 90 the window frame when the screen element is operatively extended, so as to exclude entrance of dust and insects at such time as shown in Figure 2. Horizontally swinging fasteners or catches 13 may be mounted 95 upon the bottom member of the window frame so as to be swung for engaging over the horizontal portion of the strip 12 whereby the screen element is releasably maintained in unrolled operative condition. In 100 view of the above it will be apparent that the screen element will be automatically rolled upon release of the catches 13 effected by simply swinging the latter out of engagement with the horizontal flange portion of 105 the strip 12.

This horizontal flange portion of the strip 12 projects inwardly as shown so as to move into engagement with the underside of the top window frame member 9 when the screen 110 element is rolled upon the roller 5, thereby limiting such rolling movement in a manner

to permit ready subsequent unrolling of the screen element and to present a neat appearance with the slot in the bottom of the housing 10 snugly receiving the vertical flange 5 portion of the strip 12.

The side members of the window frame indicated at 14, are provided in their outer vertical corners with rabbets 15, and snugly fitted in these rabbets are tubular sheet metal 10 guides 16 preferably formed of angularly bent strips of sheet metal of substantially C-shape in cross-section so as to have narrow slots therein from end to end and centrally of the inner sides thereof as at 17. Integral 15 with the free longitudinal edges of the guide tubes 16 are angular flanges 18 which face away from each other. These flanges form reinforcements and most desirable bearing surfaces along which are slidably 20 movable ball members 19 fastened at suitable intervals on the longitudinal edges of the screen element 6. It is thus apparent that the longitudinal edge portions of the screen element project into the guides 16 25 through the entrance slots 17 thereof, while the balls 19 engage the flanges 18 so as to maintain the screen element in taut condition and thereby resist its bending due to pressure exerted thereon either outwardly 30 or inwardly with respect to the window. The guides 16 are formed with ears 20 flush and coextensive with the outer side and inner walls thereof so as to flatly engage the adjacent right angular faces of the side 35 frame members 14 as shown clearly in Figure 3. Suitable screws or like fasteners are adapted to be passed through these ears 20 into the window frame members 14 for rigidly securing the guides 16 in place.

40 In operation, with the screen extended as shown in Fig. 2 to operative position, the catches 13 are swung out of engagement with the horizontal lower flange of the strip 12 if it is desired to raise the screen, where-

upon the spring 7 rotates roller 5 and automatically winds the screen 6 upon the roller until the horizontal flange of strip 12 engages the underside of the top frame member 9. If subsequent unrolling or lowering of the screen is desired, the horizontal flange 45 of strip 12 is engaged by the hand and the screen is unrolled by pulling downwardly thereon until the horizontal flange of strip 12 rests flatly upon the upper surface of the lower frame member of the window as shown 50 in Figure 2. The screen is then retained in lowered position by simply swinging the catches 13 to a position overlying the horizontal flange of strip 12 as shown in Figure 55 2. When the screen is unrolled its longitudinal edges will be disposed in the slots 17 of the guides 16, and the balls 19 will successively pass into the guides, the upper ends 60 of the latter being flared larger in an upward direction for facilitating the latter as 65 indicated clearly in Figures 1 and 2.

Minor changes may be made without departing from the spirit and scope of the invention as claimed.

What I claim as new is:—

In a device of the class described, including a side member in a window frame, said member provided with a rabbeted outer vertical corner, a tubular sheet metal screen guide snugly fitted in said rabbet, the guide embodying a strip of metal bent angularly on eight parallel longitudinal lines into substantially C-shaped cross-section, with a narrow guide slot therein from end to end and centrally of the inner side thereof, and ears 75 formed on the guide flush and coextensive with the outer sides and inner walls of the latter adapted to flatly engage and to be secured to adjacent right angular faces of the side frame member.

In testimony whereof I affix my signature.

GIUSEPPE DE MERCURIO.
